No. 624,530.

Patented May 9, 1899.

H. J. PAIN.
PYROTECHNIC SIGNAL.
(Application filed Feb. 7, 1898.)

(No Model.)

UNITED STATES PATENT OFFICE.

HENRY J. PAIN, OF NEW YORK, N. Y.

PYROTECHNIC SIGNAL.

SPECIFICATION forming part of Letters Patent No. 624,580, dated May 9, 1899.

Application filed February 7, 1898. Serial No. 669,351. (No model.)

To all whom it may concern:

Be it known that I, HENRY JOHN PAIN, a citizen of the United States, residing at New York, in the county and State of New York, 5 have invented a new and useful Improvement in Pyrotechnic Signals, of which the following is a specification.

My invention relates to pyrotechnic devices for signaling purposes on land and sea and 10 during either the day or night.

In carrying out my invention I provide similar interchangeable telescoping or slip holders for colored fire, each holder preferably containing fire of only one color and the color being indicated upon the exposed periphery of the holder by a band of color or letters giving the name of the color. These are slipped together and grouped in any order desired and to any extent, according to the signal to be given. The color-holders for giving the signal are adapted to use in a rocket in connection with a parachute, and by which rocket they are carried high in the air, the colored fire ignited, and the same with the parachute are blown 25 out of the rocket-head. The fires burning in successive colors indicate the signal while supported in air by the parachute. The group of color-holders may be ignited and elevated to a high point upon a flagstaff or the 30 masthead of a vessel, or the same may be connected upon the end of a stick to be held in the hand by burning.

In the drawings, Figure 1 represents by an elevation and partial section the improvement 35 applied to a rocket. Fig. 2 represents the same as suspended from a parachute and the signal burning. Fig. 3 represents the signal as upon one end of a stick to be held in the hand. Fig. 4 is a longitudinal section of a 40 group of color-holders with screw-cases, and Fig. 5 is a longitudinal section of the color-holders with slip-cases. Figs. 4 and 5 are about full size and the other figures of smaller scale.

45 The groups of slip-holders for colored fire are represented at A A'. These slip-holders are preferably made with one end larger than the other end. The smaller end receives and holds the colored fire, and the larger end receives the smaller end of the next holder having a fire of different color. The holders are 50 to be all alike and of corresponding dimen-

sions, so as to be interchangeable, but the size is immaterial.

In Fig. 4 the holders of the group A are represented as sheet-metal shells with screw-threads, the ends *a* being largest and the ends *b* smallest, all the ends *a* being the same size, so as to be adapted to receive the smaller end *b* of any other colored-fire holder, the parts 55 telescoping or screwing together to bring the surfaces of the colored fires *c* into proximity, so that one will light from the flame of the other in succession.

In Fig. 5 the holders of the group A' are 60 represented as of paper with ring centers, the ends *a'* being largest and the ends *b'* smallest, all the ends *a'* being the same size and adapted to receive and slip over the smaller end *b'* of any other holder of colored fire *c'*. Thus rings 65 of red, white, blue, yellow, and green, or white, yellow, red, green, and blue, or any other arrangement of colors desired, may be brought together for signaling.

I prefer with the paper shells to gum the 70 inner surfaces of the ends *a'* and the outer surfaces of the smaller end *b'*, so that the surfaces may be moistened previous to connecting them and adhere thereafter, so that in use they will not accidentally become disconnected.

The carrier *d*, Fig. 4, of sheet metal, is peripherally threaded to connect with the end *a* of a threaded holder, and it is provided with an eye, to which may be connected the 85 string of a parachute *D*. The carrier *d'*, Fig. 5, is received into the end of one of the paper-holders and is suitably supported or suspended.

The rocket-body *B*, as usual, contains the 90 powder and fuse and is connected to the stick *C*, and the head *B'* is removably connected to the body, preferably by the screw-thread joint *f*. The head contains the parachute and the group of slip-holders with colored fires, which 95 are preferably held in place by a packing *g* to prevent the fire from the body of the rocket injuring the parachute before and at the time said parts are blown out of the head with the colored fire ignited, the cap *B'* giving way 100 easily. The first colored fire of the group is in close proximity with the powder in the rocket to be readily lighted.

When the group of colored fires is to be

used, as shown in Fig. 3, the carrier d' is connected with the stick or holder E , and the first color to burn is preferably protected by an end cap having a lighting-fuse. These 5 groups of interchangeable colored fires are adapted for use as signals in times of peace and war from forts and fields, but particularly from vessels at sea as a means of communicating with one another by a well-recognized code of colors. They can also be used for pyrotechnic displays.

I do not herein claim a rocket with a head screwed on to give access to the parachute and signal for changing the latter, nor to the 15 yielding material around the signals to protect the parachute, as these are set forth and claimed in my application, Serial No. 669,350, filed February 7, 1898.

I claim as my invention—

20 1. A series of signals combustible in different colors, each signal having a surrounding holder in the form of an open ring larger at one end than at the other to be connected to the adjacent rings, the material or fire compound for the colored signal being in the form 25 of a cake permanently held within the smaller

end of the holding-ring and having its ends exposed so that the surface of one cake is closely adjacent to the surface of the next cake and is fired thereby without the intervention of a fuse, substantially as set forth. 30

2. A series of signals combustible in different colors, each signal having a surrounding holder of paper and a larger band projecting at one end and adapted to receive the smaller 35 part of the next holder and adhesive material for connecting the holders, the material or fire compound for the colored signal being in the form of a cake introduced and permanently held within the smaller end of the holder and having its ends exposed so that the surface of one cake is closely adjacent to the surface of the next cake and is fired thereby without the intervention of a fuse, substantially as set forth. 40

Signed by me this 29th day of January, 1898.

HENRY J. PAIN.
